[57] CLAIM

The ornamental design for a mascara smudge shield, as shown and described.

DESCRIPTION

FIG. 1 is a perspective view of a mascara smudge shield showing my new design;

FIG. 2 is a side elevational view of a mascara smudge shield shown in FIG. 1;

FIG. 3 is a top plan view thereof; and

FIG. 4 is a left hand end view of a mascara smudge shield as shown in FIG. 2.
